TIRE

Robert L. Marlowe, 2787 Boltz Road,
Akron, Ohio 44313

Filed Apr. 12, 1968, Ser. No. 11,427

Term of patent 14 years

Int. Cl. D12—14

U.S. Cl. D90—20

The figure is a perspective view of a tire showing my new design.

The dominant features of the design reside in those portions shown in full lines.

I claim:

The ornamental design for a tire, substantially as shown and described.
